UNITED STATES PATENT OFFICE.

FREDERICK E. ROTHERMEL, OF NEWARK, NEW JERSEY.

BAG LINER.

Application filed February 20, 1924. Serial No. 693,993.

This invention relates to paper liners such as are used in burlap bags and the like to prevent the sugar, salt or other contents from sifting through the bag, such liners being usually made of heavy crepe paper so that they will stretch or expand circumferentially of the bag as it is distended by its contents.

The objects of the present invention are to obtain such a circumferentially expandible bag liner which shall also have a bottom that is capable of expanding radially, or longitudinally of the creases of the crepe paper, so as to allow for distention of the bottom of the bag under the weight of its contents; to thus secure a bag liner which will not be ruptured by the weight of the contents of the bag, and avoid waste and loss; to secure a construction of expandible bottom which is simple and easily manufactured, and that at the same time is very effective; to utilize the peculiar properties of crepe paper in securing an expandible bottom, and to obtain other advantages and results as may be brought out by the following description.

Referring to the accompanying drawings, in which like numerals of reference indicate the same parts throughout the several views,

Figure 1 is a side view of a bag liner of my improved construction;

Figure 2 illustrates the crepe paper of which the bag liner is formed and which is expandible transversely of the bag only;

Figure 3 is detail view of one of the bottom corners of the bag liner inverted;

Figure 4 is a section of one of the corners of the bag liner showing the seams;

Figure 5 illustrates how the bottom of the bag liner expands in use, the dot and dash lines showing how its sides may also expand;

Figure 6 is a detail sectional view of the bottom expanded;

Figure 7 shows two sheets of crepe paper out of which my improved bag liner is made;

Figure 8 shows said sheets superposed and stitched together at one end of themselves;

Figure 9 shows the two sheets doubled outwardly apart and brought together at

the opposite side of their stitched ends to form the bottom of the liner;

Figure 10 shows how the side edges of the sheets are folded over and stitched, and

Figure 11 illustrates the bottom of the complete liner, in inverted position.

In said drawings, 1, 1 indicate two sheets of heavy crepe paper of the kind usually employed for bag liners and from which two sheets my improved bag liner is preferably formed. The sheets are laid flatwise together, each with its wrong side outermost, and then they are doubled over at one end, as at 2 in Figure 8, and stitched, as at 3. The pressure of this doubling and stitching tends to flatten the usual folds or creases of the crepe paper and thus increases its width, such increase resulting in a curved seam, as clearly shown in Figure 8.

The two sheets 1, 1 are next folded outwardly apart from each other and brought with their wrong sides together at the opposite side of the bottom seam 4, so that said seam is enclosed between the sheets, as shown in Figure 9.

The sheets where they fold, as indicated by reference numerals 5, 5 in Figure 9, are pressed and flattened somewhat and the effect of this is to produce an inward curve as shown in Figures 1 and 11, particularly as the crepe paper resumes its normal form after such folds. The result is that the bottom of the bag as seen in side view is curved toward its open end although not so sharply as the curvature of the bottom seam 4. The side edges of the sheets 1, 1 are folded over, as at 6, 6 in Figure 10, and stitched as at 7, 7, although they may be closed in any other desired way which does not interfere with the shaping of the bottom as described.

The result is a bag liner such as shown in Figures 1, 3 and 4, having an upwardly curved bottom 8 in side view and a still more sharply curved bottom seam 4, so that the inturned plait gradually increases in depth from the corners of the bag towards its middle. The result is that when the bag liner is inside of a bag which is filled, as with sugar, the bottom of the liner can expand laterally as well as circumferentially to accommodate the bulged shape of the

bottom of the bag, as illustrated in Figures 5 and 6. There is thus no rupturing of the bag liner due to the weight of the contents of the bag, especially as the amount of expansion can be increased by increasing the width of the plait 9 in folding the sheets 1, 1 of which the liner is made. My improved liner naturally assumes the shape of a filled bag, its corners fitting into the projecting corners of the bag and the middle part of its bottom widening and rounding under the weight of the contents as is common in bags. There is thus no tendency for the liner to become ruptured, and the contents of the bag are securely held against any escape through the loosely woven fabric of the bag.

Various modifications and changes may be made in manufacturing my improved bag liner, by those skilled in the art, without departing from the spirit and scope of the invention, and I do not wish to be understood as restricting myself except as required by the following claims when construed in the light of the prior art.

Having thus described the invention, what I claim is:

1. A bag liner having at its bottom an inturned plait increasing in depth from its ends toward its middle.
2. A bag liner having at its bottom an inturned plait increasing in depth from its ends toward its middle upon inwardly curved lines.
3. A bag liner of crepe paper with its creases or folds extending longitudinally of the liner, said liner having at its bottom an inturned plait increasing in depth from its ends toward its middle.
4. A bag liner of crepe paper with its creases or folds extending longitudinally of the liner, said liner having at its bottom an inturned plait increasing in depth from its ends toward its middle upon inwardly curved lines.
5. A bag liner of crepe paper with its creases or folds extending longitudinally of the liner, said liner having seams at its side edges and at its bottom an inturned plait increasing in depth from its ends toward its middle.
6. A bag liner having an inwardly curved bottom and thereat an inturned plait increasing in depth from its ends toward its middle.
7. A bag liner having an inwardly curved bottom and thereat an inturned plait increasing in depth from its ends toward its middle upon inwardly curved lines.
8. A bag liner of crepe paper with its creases or folds extending longitudinally of the liner, said liner having an inwardly curved bottom and thereat an inturned plait increasing in depth from its ends toward its middle.

9. A bag liner of crepe paper with its creases or folds extending longitudinally of the liner, said liner having an inwardly curved bottom and thereat an inturned plait increasing in depth from its ends toward its middle upon inwardly curved lines.

10. A bag liner of crepe paper with its creases or folds extending longitudinally of the liner, said liner having seams at its side edges and an inwardly curved bottom with an inturned plait increasing in depth from its ends toward its middle.

11. A bag liner of crepe paper with its creases or folds extending longitudinally of the liner, said liner having seams at its side edges and an inwardly curved bottom with an inturned plait increasing in depth from its ends toward its middle upon inwardly curved lines.

12. The method of imparting to the bottom of a bag liner of crepe paper an inturned plait increasing in depth from its ends toward its middle, which consists of stitching together two superposed sheets of crepe paper at one edge transverse to the creases of the paper, turning said sheets inner sides out upon a transverse line adjacent said stitching, and stitching together their edges paralleled to the creases of the paper.

13. The method of imparting to the bottom of a bag liner of crepe paper an inturned plait increasing in depth from its ends toward its middle, which consists in stitching together two layers of crepe paper at one edge transverse to the creases of the paper and turning said layers inner sides out upon a transverse line adjacent said stitching.

14. A bag liner of crepe paper with its creases or folds extending longitudinally of the liner, said liner having at its bottom a plait extending longitudinally of the lower edge of the liner and stitched thereto at one end of said edge to hold said plait in position until a bag with the liner in it is filled, said plait being free for the portion of said edge intermediate its ends to expand upon such filling.

15. A bag liner of crepe paper with its creases or folds extending longitudinally of the liner, said liner having at its bottom and between its side walls an inturned fold extending longitudinally of the lower edge of the liner and stitched thereto at one end of said edge to hold said plait in position until a bag with the liner in it is filled, said plait being free for the portion of said edge intermediate its ends to expand upon such filling.

16. The method of making a bag liner of crepe paper with its creases or folds extending longitudinally of the liner, which consists in forming at the bottom of the liner a fold extending longitudinally thereof to

one side edge of the liner and subsequently stitching said side edge across the end of the fold, whereby the fold is held in place until expanded by filling a bag with the liner in it.

5 17. The method of making a bag liner of crepe paper with its creases or folds extending longitudinally of the liner, which consists in forming at the bottom of the liner

an inturned fold extending longitudinally thereof to the side edges of the liner and 10 subsequently stitching said side edges across the ends of the fold, whereby the fold is held in place until expanded by filling a bag with the liner in it.

FREDERICK E. ROTHERMEL.
